UNITED STATES PATENT OFFICE.

PARKE E. SHEE, OF LANCASTER, PENNSYLVANIA, ASSIGNOR TO HARVEY B. LUTZ, OF LANCASTER, PENNSYLVANIA.

RULER.

1,027,287.

Specification of Letters Patent.

Patented May 21, 1912.

Application filed August 5, 1911. Serial No. 642,517.

To all whom it may concern:

Be it known that I, PARKE E. SHEE, a citizen of the United States, residing at Lancaster, in the county of Lancaster and 5 State of Pennsylvania, have invented certain new and useful Improvements in Rulers, of which the following is a specification.

My invention relates to improvements in 10 rulers, and the object of my invention is the provision of a flexible ruler which will bend or conform to the book or surface; which will prevent blotting or staining the surface; which can be used for ordinary 15 measuring and which can be produced at the lowest possible cost.

Another object of my invention is the provision of a ruler which is particularly useful for draftsmen and book-keepers and which 20 will provide a very desirable advertising device, by having on its face a space for advertising as well as combining other advantages.

To attain the desired objects my invention 25 consists of a ruler embodying novel features of construction and arrangement of its parts substantially as disclosed herein.

Figure 1 represents a perspective view of 30 the ruler, looking upon its top or face. Fig. 2 represents a similar view of the ruler from the back or rear face, and Fig. 3 represents a transverse sectional view on line 3-3 of Fig. 2 showing the manner of retaining the pads or blotters.

The ruler A is made of any desired size 35 and bears upon its face a scale B and preferably a flexible material of any suitable kind is employed. From each end is stamped the pair of clips C and the series of intermediate alternately arranged single clips D, 40 which receive the two sets of parallel pads or blotting strips E, composed of a series of layers to completely and snugly fit within the clips. It will be seen that the blotting strips may be readily inserted and removed 45 from the clips when desired but will not become accidentally detached. It is also apparent that the ruler can be used for measuring purposes and that my improve-

ments do not interfere with the use of the ruler for such purposes. It will also be 50 seen that the making of the ruler of flexible material renders it particularly desired for the use of book-keepers as the ruler will conform to the shape of the book and permit the drawing of a line across the entire page 55 without changing the position of the ruler and also that the blotting pad prevents soiling or staining of the book or surfaces upon which the ruler is used. It will also be seen that the clips are stamped from the 60 center of the body of the ruler and project transversely toward the edge and that I use a pair of clips at each end and a series of intermediate alternately arranged single clips, which construction permits the easy 65 application and removal of the pads and also provides a separate pad at each edge of the ruler.

One of the most important features of 70 my ruler is the construction and arrangement of the clips which open outward and permit the ready application and removal of the blotters and also permit the use of two sets of blotters. Also the end double clips and the intermediate single alternate clips 75 hold the two sets of blotters in the best possible manner while allowing easy removal and insertion of the strips as required.

I claim:

1. A ruler having at each end a pair of 80 oppositely disposed clips and a series of intermediate clips arranged along the ruler, and a series of pads fitting in said clips along each edge of the ruler.

2. A ruler made of flexible material and 85 having stamped out from the material at each end oppositely disposed clips and a series of intermediate clips arranged along the ruler, and a pair of blotting pads secured to the ruler by said clips.

In testimony whereof I affix my signature in presence of two witnesses.

PARKE E. SHEE.
